UNITED STATES PATENT OFFICE.

CARL MILLER, OF ROCHESTER, NEW YORK.

BRUSH.

957,078.

Specification of Letters Patent. Patented May 3, 1910.

Application filed May 15, 1909. Serial No. 496,168.

To all whom it may concern:

Be it known that I, CARL MILLER, a citizen of the United States of America, residing at Rochester, in the county of Monroe 5 and State of New York, have invented new and useful Improvements in Brushes, of which the following is a specification.

This invention relates to brushes, and one of the principal objects of the same is to 10 provide a brush in which the bristles are secured to removable tubes which can be readily withdrawn from the brush for cleaning.

Another object of the invention is to provide 15 a hair brush in which the bristles can be readily cleaned, means being provided for holding the bristles in the brush back and a latch being provided at the end of the brush for holding the bristles in place.

These and other objects may be attained 20 by means of the construction illustrated in the accompanying drawing, in which,—

Figure 1 is a perspective view of a hair brush made in accordance with my invention. Fig. 2 is a longitudinal section of the same on an enlarged scale. Fig. 3 is a transverse sectional view of the brush. Fig. 4 is a detail perspective view of one end of one 25 of the tubes for holding the bristles in place.

Referring to the drawing, the numeral 1 30 designates the brush back provided with a series of longitudinal bores or grooves 2, and intersecting each of said grooves at one end is a pin 3 extending through the brush back and spanning said groove. The bristles 4, preferably in tufts, are bent around a wire 5 and inclosed within a sheet metal tube 6 having a slot 7 therein through 35 which the bristles 4 extend. The tube 6

40 slides within the bore or groove 2, and the bristles extend through the slot 7 and through a slot in the back 1 of the brush, as shown more particularly in Fig. 2. To hold the tubes 6 against rotation a recess 45 or slot 8 is formed in the end of each tube to engage the pin 3 extending through the

back and through the bore or groove 2. To hold the outer ends of the tubes 6 a suitable latch 9 is pivoted at 10 to the outer end of the brush, said latch having a hooked end 50 11 adapted to engage a stud 12 to hold the latch in position to secure all the tubes 6 in place. When it is desired to clean the bristles the latch 9 is disconnected from the stud 12 and swung downwardly, after which 55 the tubes 6, together with the wires 5 and the bristles 4, are removed from the brush and cleaned, and they may then be replaced and the latch 9 swung back and engaged with the stud 12. 60

From the foregoing it will be obvious that a brush made in accordance with my invention is simple in construction; that the bristles can be quickly withdrawn from the brush and replaced after cleaning; that the 65 cost of manufacture is but slight, and that the efficiency of the brush is not interfered with.

I claim:—

The herein described brush comprising a 70 back having a series of longitudinal grooves therein, said grooves being provided with openings which extend through the under surface of the back, longitudinal wires having bristles connected thereto, tubes for inclosing said wires, said tubes with the inclosed wires being secured in said grooves, said tubes each having a recess at one end, a fastener extending through the back and into said recess for preventing the rotation 75 of said tubes, and a latch pivoted to the outer end of the brush back for preventing the longitudinal movement of said tubes and for permitting the latter to be removed with the bristles. 80 85

In testimony whereof I affix my signature in presence of two witnesses.

CARL MILLER.
